UNITED STATES PATENT OFFICE.

CHARLES H. JULL, OF RIPLEY, NEW YORK, ASSIGNOR OF ONE-HALF TO WILLIAM P. COWLES, OF ERIE, PENNSYLVANIA.

SAW.

1,187,460.

Specification of Letters Patent. Patented June 13, 1916.

Application filed December 21, 1914. Serial No. 878,302.

To all whom it may concern:

Be it known that I, CHARLES H. JULL, a citizen of the United States, residing at Ripley, in the county of Chautauqua and State 5 of New York, have invented certain new and useful Improvements in Saws; and I do hereby declare the following to be a full, clear, and exact description of the invention, such as will enable others skilled in the art 10 to which it appertains to make and use the same, reference being had to the accompanying drawings, and to the letters of reference marked thereon, forming part of this specification.

15 My invention relates to saws, and particularly to butcher-saws, wherein the saw-blade is removably secured in a form which is provided with mechanism adapted to stretch the blade taut.

20 The object of my invention is to provide a saw with detachable tension mechanism which may be removed bodily from the saw-frame when it is desired to change the same, and also to secure the tension lever to 25 said mechanism so that it will not fly out of the hand of the operative when removing the saw-blade from the frame; also to provide means to adjust the tension of the saw-blade when desired.

30 These and other features of my invention are hereinafter described and pointed out, and are illustrated in the accompanying drawings, in which:—

Figure 1, is a side view of a saw embodying my invention. Fig. 2, is a like view of a portion of the same, partially in section, enlarged. Fig. 3, is a bottom view of a portion of the same. Fig. 4, is a perspective view of the tension mechanism of my invention removed from the saw-frame. Fig. 5, is a side view of a portion of the saw-frame, and a portion of the handle in section thereon, after the tension mechanism is removed therefrom. Fig. 6, is a bottom view of the 45 tension mechanism shown in Fig. 4.

In these drawings A, indicates a metal saw-frame, and A', indicates a handle which is provided with a slot A², (see Fig. 2) into which the frame A, is inserted and secured 50 by screws a, in the usual manner. A portion of the end of the frame A, which is inserted into the slot A², is cut away at B, and has a short slot or recess B', (see Figs. 2 and 5) which extends into, or is inclosed by the

sides of the slot A², of the handle A', thereby forming a pocket which is only open at its lower end. 55

On one side of the recess B', I provide a shoulder or hook b, which tends to retain the removable tension mechanism herein-after described, from accidentally falling out of the recess or pocket B', when a saw is being removed from or being placed in the frame. Into this recess or pocket B', I insert a bar C, which is of substantially the 60 same thickness as the metal of the frame A, and is provided with a rounded end C', which acts as a bearing for said bar to pivot upon, as hereinafter described.

The bar C, is provided with an under-cut 70 shoulder c, which removably engages the shoulder or hook b, in the recess B', and is thereby prevented from accidentally falling out of the recess B'. When it is desired to remove the bar C, from the pocket B', there 75 is sufficient clearance between the rounded end C', of the bar C, and the wall of the recess B, to permit the bar C, being unhooked from the shoulder b, when the bar C, is swung sufficiently away from the frame A. 80 The bar C, is also provided with an adjusting screw C², (see Fig. 2) which passes transversely therethrough and engages the frame A, so that by turning the screw C², the lower end of the bar C can be made to 85 swing with relation to the end of the frame A.

The point end a', of the frame A, and the opposite end a², thereof, and the lower end of the bar C, are bifurcated to receive the saw-blade A³. Upon each wing of the lower or bifurcated end of the bar C, I pivot the wings of a bifurcated lever D, by means of independent or separate pivots D' D' (see Fig. 6). The wings of this lever D, are provided 90 with hooks d d, (see Figs. 3, 4 and 6) to receive a transverse stud-pin a³, in the end of the saw-blade A³, so that when the blade is in place, as shown in Figs. 1 and 2, it will be taut, and should there be a slight difference in the length of the saws, the necessary tension can be secured by adjustment of the screw C². Upon the sides of the bar C, I secure guide-plates E, by means of rivets e, which aid in maintaining the bar C, within 105 the plane of the frame A.

When it is desired to remove the saw-blade A³, from the frame A the lever D, is moved

downward from the handle A', as shown in Fig. 4, and the transverse stud-pins a^3 , removed from the hooks d d , of the lever D, when the opposite end of the blade can be disengaged from the point a' , of the frame as usual. After the saw is thus removed, the bar C, the lever D, pivoted thereon, and the guide-plates E, can be bodily removed from the frame and handle A—A', as shown in Figs. 4 and 5, and the lever D, cannot be thrown out of engagement with the rest of the saw-frame by reason of the release of the tension on the saw-blade.

Having thus fully described the construction and operation of my invention, so as to enable others to utilize the same, what I

claim as new and desire to secure by Letters Patent, is:—

In a saw, the combination of a frame having a recess in one end thereof, a bar bodily and removably fulcrumed in said recess, interlocking means to prevent the accidental moving of said bar from said recess, and a tension lever pivotally attached to said bar, substantially as described. 25

In testimony whereof I affix my signature, in presence of two witnesses.

CHARLES H. JULL.
